UNITED STATES PATENT OFFICE.

JOHN BAKER GORGEN, OF TERRE HAUTE, INDIANA.

SAD-IRON HEATER.

988,187.

Specification of Letters Patent. Patented Mar. 28, 1911.

Application filed June 16, 1910. Serial No. 567,161.

To all whom it may concern:

Be it known that I, JOHN B. GORGEN, a citizen of the United States, and a resident of Terre Haute, in the county of Vigo and State of Indiana, have invented a new and Improved Sad-Iron Heater, of which the following is a full, clear, and exact description.

Among the principal objects which the present invention has in view are: to provide a double faced sad iron and a heater supporting handle therefor constructed and arranged to permit the reversal of the said iron; to provide a heater for an iron of the character described which heats the upwardly disposed surface of the iron while the lower surface is being utilized in the operation of ironing; to provide a handle for the sad iron which is air cooled at the points of contact to limit the heat transference from the iron to the said handle; to provide an air cooled supporting member for the heater within said handle; and to provide a generator of a safe, economical and effective construction.

One embodiment of the present invention is disclosed in the structure illustrated in the accompanying drawings, in which like characters of reference denote corresponding parts in all the views, and in which—

Figure 1 is a perspective view of a sad iron and heater connected therewith, constructed and arranged in accordance with the present invention; Fig. 2 is a longitudinal view, on an enlarged scale, of a sad iron constructed in accordance with the present invention; Fig. 3 is a vertical cross section taken on the line 3—3 in Fig. 2; Fig. 4 is an end elevation of a sad iron and heater, constructed in accordance with the present invention, the lower end of the handle being removed to show the connecting boss for the handle of the iron; and Fig. 5 is a cross section taken on the line 5—5 in Fig. 2.

The class of irons to which the present invention relates is that wherein the iron is self-heated, and more particularly wherein the fluid employed is alcohol or gasolene, these liquids being adapted to be gasified by heat. The alcohol is contained in a small supply tank 6, the receiving opening of which is closed by a screw plug 7. The screw plug 7 is constructed to form a closure for the upper end of the neck 8, and is provided with a centrally disposed pipe 9. The

pipe 9 is provided at both ends with small air passages 10, 10.

The tank 6 is suitably connected with a T-pipe 11. In one extension of the T-pipe 11 is provided a passage 12, the lower end whereof is contracted to deliver within a screw threaded boring of the head of the T-connection. Within the screw threaded boring is mounted a screw 13, on the end of which is formed a cone 14 to operate as a valve to close the entrance to a small passage 15. The screw 13 is provided with a knurled head 16, and any leaking around the screw is prevented by a gland 17, in the packing space 18 whereof is provided any suitable packing material. The gland 17 is screw threaded upon the end of that branch of the T-pipe 11 in which the said screw 13 is mounted.

The T-pipe 11 is driven fixedly into the bore of a fluted tube 19. The tube 19 is elongated, and inserted in a bearing boss 20. The boss 20, on the inner end, furnishes a circular bearing for the rotation of the double faced sad iron 21.

The sad iron 21 is hollowed to form an interior chamber 22, into which are extended, from the outside, air passages 23, 23. The passages 23, 23 are disposed adjacent to the smoothing faces of the iron 21. It is within the chamber 22 that the heating torch is suspended. The iron 21 is pivoted, at the end opposite that resting on the boss 20, upon a screw 24. The screw 24 is extended through a perforation in the end 25 of a handle 26. The screw 24 is held in screw threaded engagement with a tapped hole centrally driven in a boss 27.

In the operation of ironing, when performed by a device as herein shown and described, the iron 21 is rotated on its pivotal bearings to present upwardly and alternately the smoothing faces of the said iron. The iron and handle are locked in operative position by means of a spring actuated latch 28, the head 29 whereof is adapted to engage recesses 30, 30 disposed on opposite sides of the center of the boss 27. The said latch 28 is pivotally mounted at 31 on the end of the handle 26.

It is to prevent the radiation from the handle 26 that I have provided the fluted construction for the plug 19, and have fluted the face 32 of the boss 27. By means of this construction the plug 19 and the boss 27 present, instead of a continuous surface, a

series of edges to the metal of the handle 26 with which they are in contact. The handle 26 is provided with a non-conducting hand hold 33, which may be constructed of 5 wood or any suitable material. As a fender or shield for the hand of the operator from the heat radiated from the iron 21 there is provided a shield 34. The shield 34 is fixedly secured between the uprights of the 10 handle 26, and interposed between the said hand hold 33 and iron 21.

The torch by which the iron is heated is constructed from two tubes 35 and 36. The tube 36 is superposed and supported on the 15 tube 35 by the connections 37, 37 and a saddle 38. The saddle 38 is cast with the tube 35, and forms a seat for the end of the tube 36. The tube 36 is provided with a series of jet openings 39, 39, laterally disposed in the 20 said tube, and directed to impinge the flame of the burning gas upon the under side of the upper smoothing surface of the iron 21. The torch is ignited at the jet openings 39, 39. The gas fed thereto is generated in the 25 forward end of the tube 35, and passes into the tube 36 through the connections 37, 37. The gas burned in the torch is generated from the fluid stored in the tank 6, which is fed therefrom through the passages 12 and 30 15 to the rear end of the tube 35, which is provided with a filling of asbestos fiber 40. At the forward end of the asbestos filling there is provided a fine copper wire gauze lining 41. Inwardly disposed in the tube 36, and 35 adjacent to the chamber formed by the wire gauze 41, is a plug 42, wherein is formed a pin hole passage for the delivery of gas from the chamber formed by the lining 41. Adjacent to the delivery end of the said pin 40 hole passage is an air supply opening 43, which communicates with the chamber 22 of the iron 21, and the function of which is to supply atmospheric air to the vapor as delivered from the pin hole passage, and to 45 thereby form a mixture which burns a blue flame at the openings 39, 39. The alcohol, gasoline or oil, as the case may be, which is delivered through the passage 15, percolates through the fiber 40 into the chamber formed 50 by the lining 41. When the torch is in operation, the heat generated by the flame at the openings 39, 39 is transmitted to the tube 36, and from the said tube transferred by the saddle 38 to the chamber surrounding 55 the lining 41. The heat thus produced in the chamber is communicated to the lining 41, and by the said lining to the liquid delivered thereto through the fiber 40. The effect of the heat in the chamber formed by 60 the said lining is to gasify the liquid in the said chamber. The gas thus produced is delivered through the pin hole passage in the plug 42. The current of gas passing out of the said pin hole passage draws, through the 65 opening 43, air into the forward end of the

tube 35. The air and gasified liquid are carbureted in the forward end of the tube 35, and delivered therefrom through the connections 37, 37 to the interior of the tube 36. The gas thus delivered to the tube 70 36 is of highly explosive character, and burns a blue flame at the openings 39, 39.

The operation of the sad iron when thus constructed is as follows: At the initiation of the operation the screw 13 is retracted to 75 lift the cone 14 of the pin valve to open the passage 15. The liquid contained in the tank 6 thereupon flows into the said passage, and through the fiber 40 into the chamber formed by the lining 41, and through the 80 pin hole passage in the plug 42 into the forward end of the tube 35. The liquid thus delivered is carried through a passage 44 formed in the under side of the tube 35, into a priming pan 45 integrally formed on 85 the tube 35. When sufficient oil has passed into the pan 45, the same is ignited by extending a taper, or other suitable device, through one of the passages 23, 23 to ignite the liquid contained in the pan 45. The 90 heat thus generated in the pan 45 gasifies the liquid contained in the chamber formed by the lining 41, and the same is delivered therefrom through the opening in the plug 42. The gasified oil is carbureted in the 95 tube 35 and delivered as above described to the tube 36. When thus delivered, the gas seeks exit through the openings 39, 39, and is there ignited by the flame from the pan 45. When it is observed that gas is formed 100 and properly burning at the openings 39, 39, the screw 13 is retracted to open the supply passage 15 and permit the continuous flow thereafter of the liquid stored in the said tank 6. As long as the liquid is supplied 105 from the tank 6 the heat produced by the burning of the gas at the openings 39, 39 will be sufficient to gasify the liquid when and as received in the chamber formed by the lining 41.

Having thus described my invention, what I claim as new and desire to secure by Letters Patent is:—

1. A sad iron heater embodying a torch, comprising a plurality of passage connected parallel tubes disposed in supersupported relation, one of said tubes being provided with a series of burner orifices and the other of said tubes being provided with an air inlet intermediate the ends of said tube; a generating chamber formed in said last named tube, having a delivery passage opening therefrom adjacent to said air inlet in said tube; a liquid supply tank connected with said generating chamber by suitable valve controlled passages; and a heat transferring solid metal section connecting said tubes adjacent to said generating chamber. 115

2. A sad iron heater embodying a torch, comprising a plurality of passage connected 120

- parallel tubes disposed in supersupported relation, one of said tubes being provided with a series of burner orifices and the other of said tubes being provided with an air inlet intermediate the ends of said tube; a generating chamber formed in said last named tube, having a delivery passage opening therefrom adjacent to said air inlet in said tube; a liquid supply tank connected with said generating chamber by suitable valve controlled passages; a heat transferring solid metal section connecting said tubes adjacent to said generating chamber; a priming pan disposed below said chamber; and means for delivering liquid from said tube to said pan.
5. A sad iron heater, comprising a double faced rotary hollow chambered sad iron; a heating torch therefor disposed in said chamber; an operating handle for said sad iron forming rotary bearings for said iron, a serrated bearing surface being formed between the said handle and said iron at the forward end thereof where the same impinge; and a latch pivotally mounted on said handle and adapted to engage the said iron in relatively inverted positions.
6. A sad iron heater, comprising a double faced rotary hollow chambered sad iron; a heating torch therefor disposed in said chamber; an operating handle having depending connecting extensions for connection with said iron at the opposite ends thereof, one of said extensions being provided with a fluted centrally perforated plug arranged to support the said torch; a pivot pin centrally disposed in the opposite extension of said handle in line concentrically with the said plug at the opposite end of said iron; and a serrated annular bearing surface disposed concentric with said pin to minimize the heat transference from said iron to said extension.
7. A sad iron heater, comprising a double faced rotary hollow chambered sad iron; a heating torch therefor disposed in said chamber; an operating handle having depending connecting extensions for connection with said iron at the opposite ends thereof, one of said extensions being provided with a fluted centrally perforated plug arranged to support the said torch; a pivot pin centrally disposed in the opposite extension of said handle in line concentrically with the said plug at the opposite end of said iron; a serrated annular bearing surface disposed concentric with said pin to minimize the heat transference from said iron to said extension; a latch pivotally mounted on said handle having a tail piece disposed adjacent to the hand hold of said handle and a detent head adjacent to said bearing surface; and means on said serrated bearing surface for engaging the said latch to hold the same when the said iron is reversed to present its opposite smoothing surfaces to the work.
4. A sad iron heater embodying a torch, comprising a plurality of passage connected parallel tubes disposed in supersupported relation, one of said tubes being provided with a series of burner orifices and the other of said tubes being provided with an air inlet intermediate the ends of said tube; a partition plug for said tube having the air inlet, said plug having a central delivery passage and disposed in adjacent relation to said air inlet; a non-combustible fiber plug disposed in said tube, said fiber plug being disposed in separated relation to the said partition plug to form a generating chamber in said tube; a liquid supply tank connected with said generating chamber by suitable valve controlled passages; and a heat transferring solid metal section connecting said tubes adjacent to said generating chamber.
40. A sad iron heater embodying a torch, comprising a plurality of passage connected parallel tubes disposed in supersupported relation, one of said tubes being provided with a series of burner orifices and the other of said tubes being provided with an air inlet intermediate the ends of said tube; a partition plug for said tube having the air inlet, said plug having a central delivery passage and disposed in adjacent relation to said air inlet; a non-combustible fiber plug disposed in said tube, said fiber plug being disposed in separated relation to the said partition plug to form a generating chamber in said tube; a liquid supply tank connected with said generating chamber by suitable valve controlled passages; a heat transferring solid metal section connecting said tubes adjacent to said generating chamber; a priming pan disposed below said chamber; and means for delivering liquid from said tube to said pan.
